UNITED STATES PATENT OFFICE.

HERMAN I. POTTER, OF LEONARDSBURG, OHIO.

TILE-DITCHER.

SPECIFICATION forming part of Letters Patent No. 409,424, dated August 20, 1889.

Application filed April 15, 1889. Serial No. 307,280. (No model.)

To all whom it may concern:

Be it known that I, HERMAN I. POTTER, of Leoniardsburg, in the county of Delaware and State of Ohio, have invented a new and useful Improvement in Tile-Ditchers, of which the following is a full, clear, and exact description.

My invention relates to an improvement in tile-ditchers, and has for its object to improve the construction of the tile-ditcher patented to myself May 24, 1887, No. 363,540, and to provide a means whereby the cost of manufacturing will be reduced and the machine be more readily controlled, and also be more effective in operation.

The invention consists in the novel construction and combination of the several parts, as will be hereinafter more fully described and set forth in the claims.

Reference is to be had to the accompanying drawings, forming a part of this specification, in which similar letters and figures of reference indicate corresponding parts in all the views.

Figure 1 is a side elevation of the machine. Fig. 2 is a side elevation of the endless-belt-carrying wheel. Fig. 3 is a central vertical section through the wheel. Fig. 4 is a plan view of a section of the endless belt adapted for contact with the carrier, and Fig. 5 is a perspective view of the device for regulating the tension of the endless belt.

In carrying out the invention the frame 10 of the machine consists of two pairs of side bars connected at their rear ends by a curved or upright bar and at their center by standards carried upward above the upper set of side bars to form, essentially, an arch 11.

The rear end of the machine is supported by a caster-wheel 12, the standard 13 of which is swiveled to a bearing formed in or attached to the rear ends of the lower side bars of the frame 10. To the middle parts of the lower side bars of the frame a large wheel 14 is journaled, the rim of which is grooved to form a channel in which the dirt is carried up from the bottom of the ditch.

To the side of the carrying or dirt wheel 14 a spur-wheel 15 is secured, adapted to mesh with a pinion 16, fastened upon a shaft journaled in the central standards of the frame near the upper side bars thereof, the shaft upon which the pinion 16 is secured being

also made to carry a sprocket-wheel 17. This sprocket-wheel 17 is connected by a chain belt 18 with a second sprocket-wheel attached to the shaft 19, journaled in the upper extension of the central standards of the frame, as shown in Fig. 1, and upon this shaft 19 a belt-carrying wheel 20 is rigidly secured, which belt-carrying wheel is illustrated in Figs. 2 and 3. This belt-carrying wheel constitutes one of the improved features of the machine, and consists of a hub 21, whereby it is fastened to the shaft, from which hub, at each side of its center, a series of arms 22 and 23 are made to radiate, which arms are curved outward in the direction of the ends of the hub, as best shown in Fig. 3. Each arm of the series 22 and 23 is provided with an integral lug 24, extending outward at a right angle to the body of the arm, the inner face of which lug is preferably smooth and flat, and each arm is further provided upon its outer face with an attached or integral block 25, having a sharp or knife edge, which block at the outer end is connected with or forms an integral portion of the inner flat faces of the lugs 24, the said lugs being made to extend beyond the outer longitudinal surface of the blocks. The arms of one series—for instance, 22—are so projected from the hub that they will alternate with the arms of the opposite series 23, as shown in Fig. 2. The arms are thus arranged in order that as the endless belt 26 passes over the wheel, which belt is composed of a series of plates, as hereinafter set forth, the block 25 of one set of arms will strike or engage one plate at one end and the block of the opposite series the next plate at the diagonally-opposite end.

The endless belt 26 consists of a series of plates A, preferably rectangular in general contour, and provided at one side edge, near each end, with a hook-like extension 27, which extension curves up over the plate, as shown in Fig. 4, and in the opposite side, in transverse alignment with each hook-like extension 27, a longitudinal slot 28 is produced, and the belt is formed by causing the hook-like extensions of one plate to pass upward through the slots 28 of the next plate, and so on until a complete continuous chain or belt is formed, and as the belt when completed travels over the carrying wheel or pulley 19

the hook-like extensions 27 are engaged by the several blocks 25 of the carrying-wheel, the said hook-like extensions being upon the inner face of the belt, as shown in Fig. 1. 5 Thus an effective means is provided for positively revolving the belt. After the belt is passed over in contact with the carrying-wheel 20 the forward portion of the belt is made to pass along the channel in the rear of 10 the elevating or dirt wheel 14, and from thence around the friction-pulley 28^a, held near the bottom of the machine in the movable standard 29, which standard is carried upward through the side bars of the frame 10, and 15 provided upon opposite sides, at its top, with a series of teeth 30, constituting a rack-surface, as shown in Fig. 1. The belt passes from the lower friction-pulley 28^a upward over a similar pulley 31, journaled in a hanger 32, 20 pivoted to the upper side bar of the frame at the rear end thereof.

Each of the friction-pulleys 28^a and 31 is provided with a sharp peripheral face and is capable of traveling in the center of the belt. 25 In the form of machine shown and described in my former patent these pulleys were made with flat faces; but in practice it was found that when the soil elevated was very moist they did not do effective work. The standard 29, carrying at its lower extremity the friction-pulley 28^a, is attached to the standard 33 of the plow 34, used in connection with the elevating-wheel, and the endless belt is so carried with respect to the channel of the 30 wheel 14 that the dirt raised by the plow 34 will be carried up by and between the belt and the channel-rim of the wheel 14 and will be discharged upon the ground at the side of the ditch through a spout 35, located at the 35 top of the frame of the machine, over the wheel, the inner end of which spout is so formed as to fit into the channel in the wheel and serve as a scraper to remove the dirt from the channel, as fully described in my 40 former patent. The plow - standard 33 is curved upward and rearward from the plow around the friction-pulley 28^a and forward a distance, and it is connected by a rod 35^a with a curved lever 36, pivoted near the forward end of the machine to or between the 45 lower side bars of the frame, the upper end of which lever 36 is united to a crank-arm 37, integral with a shaft 38, journaled upon the upper side bars of the frame, by a connecting-rod 39, and the said shaft 38 is manipulated by a lever-handle 40, fast to the shaft, which handle is provided with a pivoted latch 41, capable of entering one of a series of notches produced in the rack 42^a, secured to 50 the frame, as shown in Fig. 1. Thus by manipulating the said handle 40 the plow may be raised or lowered as desired through the medium of the lever 36. Tension is exerted 55 upon the belt by a spring 42, (illustrated in detail in Fig. 5,) having one end secured to a revolute shaft 43, journaled in the rear or curved ends of the side bars, which spring

is coiled and carried upward to an attachment with a rigid shaft 44, fixed in the frame above the revolute shaft 43, as shown in Fig. 1. Upon the revolute shaft one end of a chain 45 is attached, the other end of which chain is engaged with a hook 46, projected from the rear edge of the pivoted hanger 32 of the friction-roller 31. Thus by 70 unwinding the chain from the shaft 43 and securing the links to the hook 46 greater tension will be exerted upon the belt than if the chain were allowed to wind around the shaft and then be attached to the hook. 80

At each side of the racked upper end of the pulley standard or hanger 29 shafts 47 and 48 are respectively journaled, each being provided with a pinion 50, capable of contact with the said racked surface of the hanger, 85 and to the journals or shafts of each of the gear-wheels 50, upon opposite sides of the frame, cranks 50^a are attached, adapted for contact with the driver's feet, so that the driver by pushing one of his feet forward 90 raises the plow 34 and causes it to cut a shallow furrow, and by pushing the other foot forward he can cause it to cut a deeper furrow. The handle 40 of the lever and the connection between the handle and the plow 95 is more properly used for elevating the plow entirely from the ground when its services are not required.

To the inner side of the forward end of the side bars of the frame 10 are attached two 100 parallel bars 51, which are curved upon the arcs of circles and have their centers at the point where the rear ends of the side braces 52 are connected with the side bars of the frame 10, as shown in Fig. 1, so that the forward end of the said frame 10 can move up and down on a curved bar 54, having an inner 105 rack-surface, which rack-bar 54 is secured at or near the center of the forward edge by an arch 55, carrying the forward wheels 56 of the 110 machine.

To one side of the curved bars 51, which are secured to the frame 10 of the machine, are pivoted rollers 57, which rest and roll upon the side flanges formed upon the rack-bar 54, 115 said rack-bar being interposed between the frame-bars 51 and similarly curved.

The frame of the machine at the forward end is raised or lowered through the medium of a pinion 58, fixed upon a shaft journaled in the upper end of the upper side bars of the frame, which shaft also carries a miter-gear 59, and with said miter-gear a bevel-pinion 60 is made to mesh, which bevel-pinion is secured upon a shaft 61, extending above the 120 upper side bar of the frame to the rear and terminating in a suitable handle near the driver's side. Thus by turning the shaft 61 the driver can manipulate the forward end of the 125 machine.

Near the extremities of the arch 55 rack-segments 62 are rigidly secured, the rack-face of which segments are turned in the direction of the rear, as illustrated in Fig. 1, and upon 130

the said extremities of the arch, outside of the segmental racks 62, levers 63 are journaled provided with pivoted catches capable of engaging the rack - surface of the segments. 5 Upon these levers 63 the front wheels 56 of the machine are journaled. These constitute another improvement upon the old form of machine, and the purpose of this construction is to enable the operator to raise or lower both 10 of the front wheels, or only one of the same, by elevating or by depressing the levers 63, whereby the wheels may be accommodated to hillside work or to uneven ground. The arch 15 55 is further attached to the forward rack-bar 54 by means of curved braces 64, one brace extending from each extremity of the arch to a connection with the rack-bar 54 near its lower end. The front end of the frame-braces 52 is secured to the arch. It will thus 20 be observed that the forward wheels may be elevated or depressed without interfering with the position of the main body of the machine, and that the main body of the machine may be similarly adjusted without interfering in 25 the least with the position of the forward wheels.

Having thus described my invention, I claim as new and desire to secure by Letters Patent—

1. In a tile-ditcher, the combination, with a 30 frame, and a channeled elevating-wheel pivoted in said frame, of a belt - carrying wheel journaled in the frame above the elevating-wheel and consisting of a hub and two series of curved arms alternately arranged, projecting 35 from the said hub, each arm provided with an attached horizontally-arranged block, a belt passing over the carrying - wheel to a contact with the elevating-wheel, and adjustable friction-pulleys contacting with the said 40 belt, substantially as shown and described.

2. In a tile-ditcher, the combination, with a frame, and an elevating-wheel provided with a peripheral channel and journaled in the said frame, of a belt-carrying wheel journaled in 45 the frame above the elevating-wheel, consisting of a hub and opposed series of curved arms radiating from the said hub and laterally arranged, each arm provided with a horizontal block having an angular surface, a belt 50 passing over the carrying-wheel in contact with the elevating-wheel and consisting of a series of plates united by hooks integral with the edge of one plate and passing through apertures in the next plate, which hooks 55 project from the inner surface of the belt, and friction or tension pulleys held in contact with the said inner surface of the belt, substantially as shown and described.

3. In a tile-ditcher, the combination, with a 60 frame, an elevating-wheel journaled in the said frame and having a channeled periphery, and a carrying wheel or pulley journaled above the elevating - wheel, consisting of a hub and opposed series of curved arms radiating from the hub and laterally arranged, each arm provided with a horizontal block 65

having an angular surface, of a belt consisting of a series of united plates having hooks projected from its under surface near its ends, said belt passing over the carrying-pulley in 70 contact with the channel of the elevating-wheel, a friction-pulley contacting with the inner face of the belt at its lower end, a second friction-pulley contacting with the outer web of the belt at or near the center of its 75 length, said pulley being journaled in a swinging hanger, a spring-actuated shaft journaled in the frame, and a chain attached to the said shaft and to the swinging hanger, all combined for operation substantially as shown 80 and described.

4. In a tile-ditcher, the combination, with a frame, an elevating-wheel journaled in the said frame and provided with a channeled periphery, a belt-carrying pulley journaled 85 in the frame above the elevating-wheel, and a belt passing over the said pulley in contact with the channel of the elevating-wheel, of a friction-pulley contacting with the belt at its lower end, a second friction-pulley contacting with the outer web of the belt at or near its center and journaled in the swinging hanger, a shaft journaled in the frame, a spring secured to the shaft, coiled around the same, and rigidly attached to the frame, and 90 a chain attached to the spring-carrying shaft and to the said swinging hanger, all combined for operation substantially as shown and described, whereby the belt may be tightened or loosened, as desired, by lengthening or shortening the chain, as set forth.

5. In a tile-ditcher carrying an endless belt, the combination, with a pulley consisting of a hub and opposed series of outwardly-curved arms alternately arranged, each arm provided with a horizontal block having an angular face, of a belt adapted to travel over and be carried by the said pulley, said belt consisting of a series of plates, each plate being provided with hooks formed upon one 100 edge near its outer end, and transversely-aligning horizontal slots in its opposite edge and united by the hooks of one plate passing through the slots in the next plate, all combined for operation substantially as 105 shown and described.

6. In a tile dumper, the combination, with a forward arch having a segmental rack secured to each extremity, of levers pivoted to the extremities of the arch provided with 110 latches engaging the segmental racks, and forward drive-wheels journaled upon the said levers, substantially as shown and described, whereby the forward wheels may be raised or lowered together or separately and without interfering with the body of the machine, substantially as and for the purpose specified.

HERMAN I. POTTER.
